Primary Examiner — Katie Jane Stofko*(74) Attorney, Agent, or Firm* — Bereskin & Parr LLP/S.E.N.C.R.L, S.R.L.(57) **CLAIM**

The ornamental design for a gingerbread house, as shown and described.

DESCRIPTION

FIG. 1 is a front perspective view of a gingerbread house of the present design;

FIG. 2 is a front view of the gingerbread house of FIG. 1; FIG. 3 is a right side view of the gingerbread house of FIG. 1;

FIG. 4 is a top view of the gingerbread house of FIG. 1; FIG. 5 is a bottom view of the gingerbread house of FIG. 1; and,

FIG. 6 is a front perspective exploded view of the gingerbread house of FIG. 1.

The broken lines in FIGS. 1-6 illustrate portions of the gingerbread house that form no part of the claimed design.
